ELECTRIC DISCHARGE DEVICE

Hans Klemperer, Pittsburgh, Pa., assignor to
Westinghouse Electric & Manufacturing Com-
pany, East Pittsburgh, Pa., a corporation of
Pennsylvania

Application January 13, 1938, Serial No. 184,834

2 Claims. (Cl. 250—27.5)

My invention relates to vapor electric discharge devices and more particularly to means for controlling the flow of vapor in such devices incident to its operation.

It is well known to those skilled in the art that a considerable quantity of mercury vapor is developed at the cathode in excess of that required for carrying out the electrical processes. Reversals of current, for example, restriking during the non-conducting half cycle and other allied phenomena may have an adverse effect upon the proper discharge of such devices.

According to my invention, the general purpose is to provide means for increasing the current carrying capacity of such discharge devices without an appreciable increase in the arc voltage. Briefly, I divide a portion of an evacuated container into a multiplicity of separate chambers with radial openings, by securing to the inside walls of the container a plurality of annular plates. The division of the principal container into smaller chambers affords easy access for mercury vapor. The ionized mercury vapor, according to my belief, assumes more or less of an uncontrolled path due to the sudden blast of mercury vapor from the cathode upon the formation of an arc between the make-alive electrode and the cathode of such devices. By providing a deflector somewhere near the cathode spot, it is contended that the stream of vapor may be directed into the separate chambers where reflection of the vapor atoms from the container wall to regions near the anode may be substantially eliminated. Moreover, the mercury vapor expands in the condensing chambers before striking the container walls. By obstructing the free path of the ionized vapor, the life of these vapor particles is considerably reduced which otherwise may have a damaging effect if kept in an active state for too long a time before becoming deionized.

It is believed that such a construction reduces the vapor pressure in the container, increases the cooling area and especially helps to accommodate the mercury vapor by giving it an opportunity to expand before striking the container walls. Such a construction would be, in particular, suitable for such applications requiring heavy duty for one or more cycles only and after duty a long time is available for the cooling down process.

It is, therefore, an object of my invention to provide means for deflecting a vapor stream emanating from a cathode spot into separate chambers where condensation and deionization is effected.

Another object of my invention is to prevent inverse arcing or reversals in the operation of vapor discharge devices of this character.

A specific object of my invention is to provide an improved construction of an electric discharge device for effectively disposing of metallic vapor within the container of such devices incident to its operation.

Still further, it is an object of my invention to provide means for increasing the current carrying capacity of arc discharge devices of this type without increasing the probabilities of backfire.

Other objects and advantages of my invention will be apparent from the following detailed description taken in conjunction with the accompanying drawing in which the single figure is a sectional view of a vapor discharge device embodying my invention.

Referring more specifically to the drawing, my invention is shown applied to a metal tank rectifier 3 comprising a main tank portion 5 having an anode 7 suspended from the top portion of the main tank 5 and a cathode 9 of vaporizable reconstruction material, preferably mercury, disposed in the bottom of the main tank 5. A make-alive electrode 11 having a tip of high resistance material is in permanent contact with the cathode 9. Mounted on the make-alive electrode 11 is a deflecting plate 13, preferably made of steel. A plurality of annular plates 15 having radial openings 16 are mechanically secured to the walls 17 of the metal tank 5, preferably, near the lower portion thereof. The plates 15 thus mounted, form a plurality of chambers 19 wherein mercury vapor enters and condenses as I shall herein- after point out in greater detail. I prefer to slope the annular plates 15 somewhat downwardly toward the deflecting plate 13 mounted on the make-alive electrode 11 to render them more effective in entrapping the mercury vapor swept along with a rectifying arc that is being maintained between the cathode 9 and the anode 7.

The walls 17 of the metal tank 5 may be cooled by circulating a liquid through a water jacket 21 located about the main tank 5. Since the deflecting plate 13 protects striking of the lower portion of the anode 7 against the vapor stream, it is common practice to substantially surround the sides of the anode 7 by a suitable insulator 23, although it is to be understood that this does not form part of my invention.

In the operation of the device, an auxiliary arc is first initiated between the make-alive electrode 11 and the cathode 9 by passing a current through the former from some suitable

source 25 such as a grid-controlled device, thus liberating electrons and evaporating mercury. By impressing an electric field between the anode 7 and the cathode 9, so that the anode 7 is positive with respect to the cathode 9, the arc will transfer to the anode 7 and the electrons liberated at the cathode 9 will travel along the lines of force towards the anode 7. However, the main arc is deflected somewhat towards the walls 17 of the metal tank 5 by the deflecting plate 13 on the make-alive electrode 11. A stream of heated mercury vapor carried along with the arc is deflected towards the tank walls 17 instead of spreading in all conceivable directions. As a result, the mercury vapor is effectively guided and directed away from the anode 7 in such manner that the anode 7 is not subjected to the vapor blast.

The areas or chambers 19 formed by the annular plates 15 provide sufficient condensing surface for the mercury vapor, which, upon entering the plurality of chambers 19, expands before condensing on the walls 17 of the container 5 or on the walls of the annular plates 15. Without the condensing chambers 19, the free path of the ionized vapor atoms might produce a damaging effect by keeping the ions alive long enough so that their reflection from the tank walls 17 towards the anode 7 would not be blocked.

Although I provide a deflecting plate 13 above the make-alive electrode 11 to control the direction of the stream of mercury vapor, all other deionizing means between the cathode 8 and the anode 7 which may increase the arc drop could be eliminated.

While I have shown and described certain

specific embodiments of my invention, it will be apparent that changes and modifications can be made therein without departing from the true spirit or scope of the accompanying claims.

I claim as my invention:

1. A vapor-electric device comprising an evacuated metallic vessel, a vaporizable cathode in said vessel, an anode cooperating with said cathode, a make-alive electrode in permanent contact with said cathode, a plurality of annular plates secured to the side walls of said vessel to provide a plurality of substantially separate condensing chambers, said plates having openings to provide a substantially unobstructed path between said anode and cathode, a substantially 16 conical baffle adjacent the cathode surface to direct vapor rising from said cathode into said condensing chambers, and means for cooling said condensing chambers.

2. A vapor-electric device comprising an evacuated metallic vessel, a vaporizing cathode in the bottom of said vessel, an anode cooperating with said cathode, a substantially centrally located make-alive electrode in permanent contact with said cathode, a plurality of annular plates 25 secured to the side walls of said vessel to divide the vessel into a plurality of substantially separate condensing chambers, said plates having aligned central openings providing a substantially unobstructed arc passage between said anode 30 and cathode, an upwardly diverging baffle mounted on said make-alive electrode for diverting the cathode vapor from said arc passage into said condensing chambers, and means for cooling said condensing chambers.

HANS KLEMPERER.
